911;

UNITED STATES PATENT OFFICE.

ROBERT ARMISTEAD, OF RICHMOND, VIRGINIA.

DESIGN FOR A MEDAL OR MEDALLION.

SPECIFICATION forming part of Design No. 12,360, dated July 12, 1881.

Application filed May 21, 1881. Term of patent 34 years.

To all whom it may concern:

Be it known that I, ROBERT ARMISTEAD, a citizen of the United States of America, residing at Richmond, in the county of Henrico and State of Virginia, have invented a certain new and original Design for Medals or Medallions; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a view of the obverse side of the medal, and Fig. 2 shows the reverse side of the medal.

The object of the design is to commemorate the surrender of the British forces to the commander of the United States forces at Yorktown, Virginia, the 19th day of October, A. D. 1781. Hence the leading features of the design are the busts of Washington and La Fayette on the obverse, set in profile and cast in low relief, and having on the plate, over the profiles, the words: "Centennial, Yorktown, Va., " and under the figures the date in figures, "1881," substantially as shown in Fig. 1 of the drawings; and on the reverse side, in low relief, is a representation of the surrender at Yorktown in miniature, consisting of figures of men in military array, with the words "Surrender at

Yorktown, Va., " over the representation, and at the base are the words and figures "Oct. 19, 1781," substantially as shown in Fig. 2 of 35 the drawings.

The medals or medallions are cast or struck from metal, and are circular in form.

I claim—

1. A design for a medal or medallion, substantially as herein shown and described, which consists of the busts of Washington and La Fayette set in profile and cast in relief. 40

2. The design for a medal or medallion herein shown and described, the same consisting on the obverse side of the busts of Washington and La Fayette set in profile and cast in low relief, and the words "Centennial, Yorktown, Va., " over the portraits, and the figures "1881" at the base thereof. 45

3. The design for a medal or medallion, substantially as herein shown and described, which consists in the combination of the busts of Washington and La Fayette set in profile and cast in relief on one side, and the representation in miniature of the surrender at Yorktown, consisting of figures of men in military array cast in relief on the other side. 55

In testimony whereof I affix my signature in presence of two witnesses.

ROBERT ARMISTEAD.
